COMPRESSED AIR COOLER

Carl E. Staky, Wausau, Wis., assignor to D. J. Murray Manufacturing Co., Wausau, Wis., a corporation of Wisconsin

Application February 12, 1942, Serial No. 430,528

3 Claims. (Cl. 257—198)

The present invention relates generally to improvements in the art of heat exchange, and relates more specifically to various improvements in the construction and operation of coolers for extracting heat and moisture from compressed air or the like being delivered from a compressor.

An object of the invention is to provide an improved air cooling unit which is simple and compact in construction, and which is moreover automatic and highly efficient in operation.

It is common commercial practice in the art of compressing air or other gas with the aid of a compressor, to provide a so-called after-cooler for reducing the temperature of the compressed fluid and for removing the liquid of condensation therefrom. While some of the prior cooling assemblies of this general type are quite satisfactory in operation, most of them are objectionable either because they are too complicated and bulky, or because they require considerable attention and are not sufficiently reliable in operation, or because they are too costly to construct and cannot be readily furnished as a unitary structure the capacity of which may be readily varied to suit different conditions of operation. Many of the prior compressed air coolers have therefore been relatively objectionable for one reason or another, and could not be standardized so as to minimize the cost of manufacture thereof.

It is therefore a more specific object of my present invention to provide a new and useful compressed air cooler which obviates all of the above mentioned difficulties and objections, and is therefore extremely efficient and dependable in use.

Another specific object of this invention is to provide an improved compressor after-cooler, which occupies least space considering the capacity thereof, and which can be produced by merely assembling any desired number of standard finned heat transfer sections in series and in a simple manner.

A further specific object of the invention is to provide an improved cooling unit especially adapted for co-operation with the discharge line of an air compressor, which functions automatically to both effectively cool the compressed air and to remove condensate therefrom.

Still another specific object of my invention is to provide an improved cooler assembly all parts of which are readily accessible for inspection and removal, in which the heat transfer sections are amply protected, and which can be manufactured and sold at moderate cost.

These and other specific objects and advan-

tages of the present invention will be apparent from the following detailed description.

A clear conception of the several features constituting the present improvements, and of the mode of constructing and of operating air cooler units embodying the invention, may be had by referring to the drawing accompanying and forming a part of this specification wherein like reference characters designate the same or similar parts in the various views.

Fig. 1 is a side elevation of one of the improved compressed air cooling units, portions thereof having been broken away and shown in section in order to reveal normally concealed structure;

Fig. 2 is an end view of the cooling assemblage of Fig. 1, with portions likewise broken away;

Fig. 3 is an enlarged part sectional side view of one of the standard finned heat transfer sections used in producing the new cooling unit;

Fig. 4 is a similarly enlarged transverse vertical section through the finned heat transfer section of Fig. 3, taken along the line 4—4.

While the invention has been shown herein as being embodied in a water cooled compressed air cooling and condensate extraction unit comprising two adjacent sets of five superimposed standard finned heat transfer sections especially adapted for use as an after-cooler, it is not the intention to thereby unnecessarily restrict the scope or utility of the improvement, since the assemblage may also be used as an interstage cooler for multiple stage compressor systems.

Referring to the drawing, the improved compressed air cooling and condensate removing unit shown therein, comprises in general, a main rectangular outer casing 6 having therein spaced parallel upright partitions or walls 7 forming a medial water circulating chamber 8; two adjacent series each comprising five superimposed interchangeably similar and externally finned heat transfer sections 9 each having opposite upper and lower end bosses 10, 11 respectively, snugly mounted in openings formed in the adjacent walls 7 so that the sections 9 are suspended horizontally within and span the chamber 8; a pair of compressed air supply pipes 12 communicating with the interiors of the upper sections 9 of the two series through the upper bosses 10 thereof; a return bend 13 connecting the lower boss 11 of each radiator section 9 with the upper boss 10 of the section directly therebeneath; a pair of cooled air outlet pipes 14 communicating with the interiors of the lowermost radiator sec-

tions 9 of the two series through the lower bosses 11 thereof; a condensate discharge pipe 15 communicating with the lowermost portion of each air outlet pipe 14 and leading to a trap; a cold water supply pipe 16 communicating with the lower portion of the chamber 8 beneath the finned sections 9; and a spent cooling water discharge pipe 17 communicating with the upper portion of the chamber 8 above the radiator sections 9, and being connected to a suitable drain not shown.

The main casing 6 which provides a protective housing for the entire cooling unit, is open for inspection at the top and may be formed of sheet metal or the like. In addition to the water supply and discharge pipes 16, 17, the casing 6 is provided with a drain plug 18 at the lower portion of the chamber 8, and with an overflow connection 19 at the upper extremity of the cooling chamber. The parallel transverse walls 7 which form the chamber 8 and from which the finned cooling sections 9 are suspended, are rigidly interconnected and spaced apart a definite distance, by means of tie-rods 20 and spacer sleeves 21 located in pairs above and below the heat transfer sections 9; and the entire wall and finned section assemblage may be removably mounted within the main casing 6 so as to permit bodily insertion and removal of the assemblage. The tie-rods 20 are provided with clamping washers 22 and nuts 23 for firmly uniting the parts, and serve to retain the bosses 10, 11 of the heat transfer sections 9 snugly confined within circular openings 24 formed in the walls 7. The edges of the walls 7 need not necessarily have water-tight coaction with the adjacent internal surfaces of the main casing 6, since it is immaterial whether some cooling liquid seeps from the space 8 into the spaces beyond these walls 7; but the coaction between the walls 7 and the main casing 6 should be sufficiently loose so as to permit ready removal and insertion of the coil and wall assemblage.

The finned heat transfer sections 9 are of relatively standard and interchangeable construction, as shown in detail in Figs. 3 and 4, and each of these sections comprises an elongated, relatively flat hollow body 25 formed integral with the corresponding bosses 10, 11, and a plurality of parallel radiating fins 26 firmly secured to or formed integral with the body and extending from end to end thereof. Besides the upper and lower bosses 10, 11, each section 9 is furthermore provided with opposite end plugs 27, and in the final assemblage, these plugs 27 may contact the adjacent surfaces of the suspension walls 7. The return bends 13 may be formed in any desired manner, but as shown, each of the return bends 13 which connect the adjacent bosses 10, 11 of the sections 9, consists of three pipe nipples 28, 29, 30, two elbows 31, 32, and a union 33, as shown in Figs. 1 and 2, and since all of these elements are standard pipe fittings, they permit rapid and convenient assembly and dismantling while affording tight connections when properly assembled. The air supply and outlet pipes 12, 14 and the condensate discharge pipe 15, may all be formed of standard piping and fittings, and the upper end of the condensed liquid discharge pipe communicates with a suitable trap 34 which may be of relatively standard design adapted to permit delivery of the liquid without permitting escape of compressed air from the system.

During normal operation of the improved compressed air cooler and condensate remover, and

assuming that the unit has been properly constructed, assembled and connected up to the compressor and source of cooling liquid, the compressed air will be constantly admitted to the uppermost cooling sections 9 from the compressor through the supply pipes 12 and after flowing downwardly through the successive sections 9 in series, will be discharged to a receiver through the air delivery or outlet pipes 14. Simultaneously with this down-flow of compressed air through the interiors of the finned sections 9, a constant stream of cold water should be admitted to the lower portion of the cooling chamber 8 through the supply pipe 16, and this cooling liquid will gradually rise along the finned sections 9 and will extract heat from the oppositely advancing stream of compressed air, through the radiator bodies 25 and fins 26, thus gradually cooling the air and condensing excess moisture therefrom. The spent cooling water will eventually be delivered from the chamber 8 through the discharge pipe 17, and the water of condensation will flow downwardly with the air stream, through the sections 9 and the lower portions of the outlet pipes 14, where it will escape into the pipes 15. After rising through the pipes 15 due to the air pressure within the system, the condensate will escape past the trap 34, and relatively dry and cool air under pressure will thus be constantly delivered from the cooling unit through the pipe 14. The degree of cooling will depend upon the temperature of the compressed air and of the cooling liquid, but it is to be noted that cooling is effected by counter flow of the air and liquid, and that the cooling operation is entirely automatic.

By virtue of the fact that the entire cooling unit may be constructed and assembled from standard sheet material such as steel or other metal, piping, pipe fittings and heat transfer sections, the cost of construction is reduced to a minimum and manufacture thereof is greatly facilitated. While a cooling unit comprising two adjacent sets each consisting of five superimposed sections 9, has been shown herein by way of illustration, the cooler may embody any desired number of sets and any desired number of sections in each set, depending upon the performance required; and one or more air supply and outlet pipes 12, 14 may be utilized. The specific formation and co-operation of the finned sections 9 with the walls 7 is important, since the integral eccentrically disposed end bosses 10, 11 of the sections 9 which snugly coat with the non-aligned openings 24 of the walls 7, positively prevent possible rotation or displacement of the sections 9 relative to the suspension walls 7; and the tie-rods 20, sleeves 21, washers 22, and nuts 23 facilitate assembly of the walls 7 and heat transfer radiator sections 9 outside of the main casing 6, and application of the return bends 13 to the hollow bosses 10, 11. The finned heat transfer radiator sections 9 may be readily manufactured and have maximum heat radiating capacity considering the space occupied, and their use also provides flexibility in construction, since all of the sections 9 are of identical and symmetrical formation and are therefore interchangeable with each other and may be reversely positioned. The assembly of the elements so that the compressed air flows in a direction opposite to the direction of flow of the cooling liquid, also insures most efficient cooling, and the unit functions automatically when prop-

erly initially adjusted to produce the desired results.

From the foregoing detailed description of the construction and operation of the improved cooling device, it will be apparent that my present invention provides a cooling unit for compressed air or the like, which is extremely simple and compact in construction, and which is moreover highly efficient in operation. The improved counter-flow cooling assemblage can obviously be readily assembled, inspected, and dismantled, and may be manufactured in sizes to meet various operating conditions, at moderate cost. The improved cooler has proven highly satisfactory in actual use, and while the assemblage is especially adapted for use in cooling compressed air and to extract liquid of condensation therefrom, with the aid of cooling water, it may also be put to other uses in other industries.

It should be understood that it is not desired to limit this invention to the exact details of construction or to the precise mode of use and operation, herein shown and described, for various modifications within the scope of the appended claims, may occur to persons skilled in the art.

I claim:

1. In combination, a main casing, parallel upright walls loosely and removably disposed within said casing and having vertically spaced openings therein of which the openings in one wall are out of horizontal alinement with those in the other wall, a series of superimposed finned elongated heat transfer sections horizontally spanning the space between said walls and each having a single internal chamber and non-aligned hollow opposite end bosses communicating with upper and lower portions of said chamber and being slip-fitted within a set of said wall openings so as to prevent rotation of said sections relative to said walls, tie-rod assemblages interconnecting said walls so as to definitely maintain the same in proper spaced relation and to retain said bosses within said openings, removable conduit means connecting the lower boss of each section with the upper boss of the adjacent lower section to provide a continuous downwardly directed zig-zag passage for fluid extending throughout said series, means for constantly admitting cooling medium to the lower portion of the space between said walls, and an outlet for spent cooling medium at the upper portion of said space.

2. In combination, a main casing, horizontally

spaced upright walls loosely and removably disposed within said casing and having vertically spaced openings therein of which the openings in one wall are out of horizontal alinement with those in the other wall, a series of superimposed elongated heat transfer sections horizontally spanning the space between said walls and each having a single internal chamber and non-aligned hollow opposite end bosses communicating with the upper and lower portions of said chamber and being slip-fitted within a set of said wall openings so as to prevent rotation of said sections relative to said walls, tie rod assemblages interconnecting said walls so as to definitely maintain the same in proper spaced relation and to retain said bosses within said openings, removable conduit means connecting the lower boss of each section with the upper boss of the adjacent lower section to provide a continuous downwardly directed zig-zag passage for fluid extending throughout said series, and means for introducing cooling liquid into the lower portion of the space between said walls and for delivering spent cooling liquid from the upper portion thereof.

3. In combination, a main casing, parallel upright walls loosely and removably disposed within said casing and having vertically spaced openings therein of which the openings in one wall are out of horizontal alinement with those in the other wall, a series of superimposed elongated heat transfer sections horizontally spanning the space between said walls and each having a single internal chamber and non-aligned hollow opposite end bosses communicating with the upper and lower portions of said chamber and being slip-fitted within a set of said wall openings so as to prevent rotation of said sections relative to said walls, tie rods connecting said walls, sleeves embracing said tie rods and coacting with the adjacent surfaces of said walls and with said rods so as to definitely maintain the walls in proper spaced relation and to retain said bosses within said openings, removable return bends connecting the lower boss of each section with the upper boss of the adjacent lower section to provide a continuous downwardly directed zig-zag passage for fluid extending throughout said series, conduit means for admitting cooling liquid to the lower portion of the space between said walls, and an outlet for spent cooling liquid communicating with the upper portion of said space.

CARL E. STAKY.
